Lundgren, Paula R. et al., Design U.S. Appl. No. 29/556,771, filed Mar. 3, 2016 entitled "Tire Tread".

Primary Examiner — Robert M. Spear(74) *Attorney, Agent, or Firm* — Shaun J. Fox(57) **CLAIM**

The ornamental design for a tire, as shown and described.

DESCRIPTION

FIG. 1 is a side perspective view of a tire showing our new design, it being understood that the claimed pattern is repeated throughout the circumference of the tire, the opposite side being the same as that shown;

FIG. 2 is a front elevational view thereof, the opposite side being identical thereto;

FIG. 3 is an enlarged fragmentary front elevational view thereof;

FIG. 4 is a side elevational view of the left side thereof; and,

FIG. 5 is a side elevational view of the right side thereof. In the drawings, the broken lines depict environmental subject matter only and form no part of the claimed design.
